UNITED STATES PATENT OFFICE.

WILLIAM SPEER AND ARTHUR LOUIS SPEER, OF BALTIMORE, MARYLAND.

CENTRIFUGALLY-OPERATED BRAKE.

1,162,411.

Specification of Letters Patent. Patented Nov. 30, 1915.

Application filed October 2, 1909. Serial No. 520,756.

To all whom it may concern:

Be it known that we, WILLIAM SPEER and ARTHUR LOUIS SPEER, citizens of the United States, residing at Baltimore city, in the State of Maryland, have invented a new and useful Centrifugally-Operated Brake, of which the following is a specification.

Our invention relates to improvements in centrifugally operated brakes, and power mechanism attached to a driven mechanism controlled by said brakes; and the objects of our improvements are, first, to provide an improved hoisting mechanism, provided with a centrifugal brake and operated by a power mechanism having free movement in one direction, to prevent sudden shocks or jars in operation; second, to provide an improved means of controlling a lowering mechanism, and third, the providing of a hoisting and lowering mechanism, with suitable operating mechanism and control.

We attain these objects by the mechanism illustrated in the accompanying drawings in which—

25 Figure 1 is a front view of the entire appliance installed; Fig. 2 is a view taken at right angles to that shown in Fig. 1; Fig. 3 is an enlarged view partly in section of the automatic dumb waiter; Fig. 4 is an enlarged view of the dumb waiter head shown in Fig. 1 and having the hub of the driving pulley exposed in order to show the releasing mechanism; Fig. 5 is a face view showing the governor weights in place; Fig. 6 is an enlarged view of the governor plate; Fig. 7 is a view of the governor plate taken at right angles to that shown in Fig. 6; and Fig. 8 is an enlarged view of the governor weights.

40 Similar numerals refer to similar parts throughout the several views.

1 is the casing.

2 is the main driving shaft.

3 is the main gear keyed to the main shaft 2.

4 is the first intermediate gear meshing with the main gear and keyed to intermediate shaft 24.

5 is the second intermediate gear keyed to intermediate shaft 24 and meshes with and drives governor gear 6. Governor gear 6 runs loose on main shaft 2 is integral with sleeve 20 and drives or is retarded by brake gear 7.

55 7 is the brake gear running idle on brake shaft 8 and meshing with governor gear 6.

8 is the brake shaft operating through casing 1 with a longitudinal but not a rotary movement one end of which is formed into a head 9 which head 9 upon the longitudinal movement of brake shaft 8 clamps brake gear 7 between said head 9 and casing 1 thus braking the same.

10 is an inclined collar secured by means of pin 11 or otherwise secured to brake shaft 8.

12 is the brake incline operating free on brake shaft 8 and against incline collar 10. To brake incline 12 is secured brake lever 13 at the end of which is eye 14 to which is attached the brake rope 32.

16 is the hoisting pulley secured to main driving shaft 2 and over which operates hoisting cable 30.

17 is a leather disk secured to governor plate 18.

18 is the governor plate having integral therewith inclines 19.

20 is a sleeve secured to governor gear 6 flat on one side and which operates loose on main shaft 2 and over which operates governor plate 18 and to which it is rotatively secured.

21 are studs secured into sleeve 20 and upon which operates governor weights 23. 85

22 are springs tending to keep governor weights 23 closed or in normal position.

23 are governor weights which operate on studs 21 and inclines 19 thus braking main driving gear 3 and governor gear 6. 90

24 is the intermediate shaft upon which are secured intermediate gears 4 and 5.

25 is the driving pulley automatically secured to intermediate shaft 24 and over which operates hand rope 31. 95

26 is a collar keyed to intermediate shaft 24.

27 are graduated rollers.

28 is a tapered recess formed in driving pulley 25 and in which work graduated rollers 27.

29 is a spring tending to keep graduated rollers 27 engaged.

30 is the hoisting cable.

31 is the hand rope.

32 is the brake rope.

33 is the car.

The operation of our invention is as follows—Having installed the dumb waiter in the usual manner, we use the hand rope to hoist the car. When the car is at the proper landing the brake is applied by hand and

the car stops. The lowering is by gravity, driving pulley 25 and rope 31 runs free and in stopping the dumb waiter, shock which might be caused by the sudden stopping of a long rope and pulleys running at high speed is prevented by means of the automatic attachment of driving pulley 25 to intermediate shaft 24.

Having thus described our invention what we claim and desire to secure by Letters Patent is—

1. The combination with a pulley, of a rotatable and longitudinally movable brake for controlling the movement of said pulley, means actuated by the speed of movement of said pulley for automatically throwing said brake into operation, a gearing mechanism operating said pulley, a power mechanism applied to said gearing mechanism, automatic means of attaching said power mechanism to said gearing mechanism whereby the power mechanism has a loose movement in one direction of operation from the gearing mechanism.
2. The combination with a pulley, of a brake for controlling the movement of said pulley, means actuated by the speed of movement of said pulley for automatically throwing said brake into operation, a gearing mechanism operating said pulley, a power mechanism applied to said gearing mechanism, automatic means of attaching

said power mechanism to said gearing mechanism whereby the power mechanism has a loose movement in one direction of operation from the gearing mechanism.

3. In a dumb waiter, a driving shaft, a driven shaft, positively operative mechanism connecting said two shafts, a governor brake operating to control the speed of one of said parts consisting of, a pair of rotating parts provided with means of automatically braking said parts upon the increase of speed of one of said parts, the said two parts being positively geared to operate at different speeds.

4. In a dumb waiter, a driving shaft, a driven shaft, positively operative mechanism connecting said two shafts, a governor brake operating to control the speed of one of said parts consisting of, a pair of rotating parts provided with means of automatically braking said parts upon the increase of speed of one of said parts, the said two parts being positively geared to operate at different speeds and positively operative mechanism between said brake and the one of said shafts.

WILLIAM SPEER.
ARTHUR LOUIS SPEER.
